180,178

STERILIZER

Joseph P. Duray and William Kurz, Chicago, Ill., assignors to Precision Scientific Company, Chicago, Ill., a corporation of Illinois

Application December 22, 1955, Serial No. 39,430

Term of patent 14 years

(Cl. D83—1)

Fig. 1 is a perspective view of a sterilizer, showing our new design and with cover closed.

Fig. 2 is a perspective view with cover open.

We claim:

The ornamental design for a sterilizer, as shown.

References Cited in the file of this patent

Aloe Catalog, Sharp & Smith Hospital Division, © 1942, page 512, upper right, Castle Sterilizer.
Surgical Selling Company Catalog, © 1948, page 217, left side of page, American Instrument and Pelton Sterilizers.